Patented Jan. 30, 1917.

UNITED STATES PATENT OFFICE.

oi

WILLIAM JAMES HAYNES, OF ST. LOUIS, MISSOURI.

AUTOMATIC VALVE.

1,213,870.

Specification of Letters Patent. Patented Jan. 30, 1917.

Application filed October 27, 1916. Serial No. 128,007.

To all whom it may concern:

Be it known that I, WILLIAM JAMES HAYNES, a citizen of the United States, residing at the city of St. Louis and State of 5 Missouri, have invented a new and useful Automatic Valve, of which the following is a specification.

This invention relates to improvements in 10 automatic valves and consists in the novel 15 design, arrangement and combination of parts in such a valve as hereinafter more fully disclosed.

An object of the invention is to provide 20 a valve adapted primarily to control the supply passage to a tank or container whereby a predetermined level of liquid 25 may be maintained in the tank.

Another object of the invention is to produce 30 a valve of simple and durable construction which is weighted to maintain the valve in open position, and which is operated to closed position after a predetermined flow of water through the valve.

Additional advantages attainable from 35 the present construction will be clearly apparent to those skilled in the art to which this invention relates without specific mention from the following detailed disclosure taken in connection with the accompanying 40 drawing, in which—

Figure 1 is an elevation of a tank or container equipped with a supply passage having the valve of the present invention applied thereto. Fig. 2 is a plan view of the 45 valve structure detached and having portions broken away. Fig. 3 is a front end elevation of the valve partially in section to more fully disclose certain features of the construction. Fig. 4 is a vertical section through the valve taken substantially on the line 4—4 of Fig. 2. Fig. 5 is a vertical section through the valve taken substantially on the line 5—5 of Fig. 2. Fig. 6 is a perspective view of the arm controlling the valve plug.

In the embodiment of the invention illustrated in the drawing, the valve is shown applied to an inlet passage 1 of a tank 2. The valve proper comprises a casing 3 50 which is substantially in the form of a T-shaped union, that is to say it has a tubular horizontally disposed body 4, the upper

wall of which is projected upwardly forming the extension 5. The main body of the extension 5 is rectangular in form and comprises a squared body cast integral with the body 4 and having formed at the top integrally therewith a polygonal casting 6 having a cylindrical threaded opening 7. The body 4 has polygonal ends 8 and 9 respectively, said ends being threaded interiorly. The polygonal portions 6, 8 and 9 respectively are provided for wrench engagement so that the valve may be attached to the connections. The body portion 4 has a transverse partition wall 10 integrally formed therewith, said partition wall having an axial port or opening 11. The end of the supply passage 1 discharges into the end of the body 4 beyond the partition 10, 70 said supply passage being in threaded connection with the end 8 of the body. Upon the inner wall of the body 4 adjacent to the inner face of the partition 10 are formed ribs or lugs 12, the inner edges of said lugs 75 being rounded so as to receive and support the valve plug 13.

The valve plug 13 is a cylindrical body having a flat forward face and a rounded projection 14 from its rear face. There is 80 a threaded opening in the front face of the valve plug 13 adapted to receive the screw 15 by means of which a rubber washer or gasket 16 is held against the front face of the valve plug. The valve plug is adapted 85 to slide to and away from the partition wall 10 thereby controlling the inlet port 11.

The front wall of the extension 5 has an exteriorly threaded hollow projection 17 designed to receive the packing nut 18 and to 90 form a packing gland with the packing 19 around the casting 20. The casting 20 comprises a hollow cylindrical section 21 which is adapted to be received within the packing gland comprising the parts 17, 18 and 19, 95 said section 21 having an inwardly extending squared portion 22 at the end of which is a rounded projection 23 having a depression 24 on its inner face. The projection 23 is adapted to seat in a recess formed in a boss 100 25 on the rear wall of the extension 5 of the main valve casing, there being within the recess and between a wall of the boss a ball 26. The casting 20 has an upwardly extend-

ing leg 27 from the forward end of the tubular portion 21 which connects into a leg 28 extending upwardly at an acute angle from the portion 27 of the casting 20.

- 5 Through the wall of the portion 22 of the casting 20 is an opening 29 and extending from the side wall of the casting 20 at the elbow of the sections 27 and 28 is a substantially horizontally disposed solid arm 30.
- 10 The casting 20 constitutes a rocking member for controlling the arm which in turn controls the movement of the valve body 13. The arm includes the rectangular frame 31 which is adapted to embrace the squared portion 22 of the casting 20 and to be locked in position by the set screw 32 operating through the threaded boss 33. A lug 34 projects from the lower end of the frame and is adapted to move to and away from 15 the projection 14 of the valve body 13 as the casting 20 is rocked. A threaded plug 35 adapted to be engaged in the end 9 of the body 4 has on its inner face a lug 36, so that when the plug is mounted in place it will 20 limit the outward rocking movement of the arm. A counter-weight 37 is attached to the end of the arm 30 and is adapted to rock the casting 20 so that the lug 34 will move against the abutment 36 to the limit of its 25 movement away from the valve body 13. When the arm is in this position the valve 30 is opened.

Threaded into the end of the leg 28 of the casting 20 is a connection 38 which opens 35 into a container 39 which is so adjusted that when it is filled to a predetermined level, the casting 20 will swing and thereby move the arm 34 against the extending portion 14 of the valve body and cause the closing of 40 the port 11, shutting off the water supply. The container 39 has an opening 40 in the upper portion thereof, so that the air may 45 exhaust therefrom as the container is filled. There is a connection 41 from the threaded opening 7 of the valve body into the tank 2.

From the foregoing it will be understood that the operation of the valve is as follows: Normally the weight 37 holds the parts in position so that the valve body will be away 50 from the port 11, permitting the flow of water therethrough. The water rises in the valve chamber and passes through the connection 41 into the tank 2 and also through the port 29 in the casting 20, from whence it 55 flows upwardly into the container 39. When the water has reached a predetermined level in the container 39, which of course will be the same water level as is attained in the tank 2, the casting 20 is swung, thereby carrying the projection 34 against the extension 14 of the valve body and causing the valve body to be pressed against the inner face of the partition wall 10, effectively to close the port 11. When the level of the water in the

95 tank 2 falls below the predetermined height the water in the container 39 drops correspondingly and the weight 37 then overbalances the weight of the fluid in the container 39, rocking the casting 20 and causing the arm 34 to be carried away from 100 the valve body, again opening the passage way 11.

It will be understood that the principle of the present invention may be embodied in modified structure, and that the invention 105 does not reside alone in the specific details shown and described. I do not desire to limit myself therefore, to the exact structure disclosed, but

What I claim and desire to secure by Letters Patent is:—

1. A valve, comprising a valve casing, an influent port to said valve casing and an effluent opening from said valve casing, a valve body controlling said influent port, a 110 hollow rocker arm having one end thereof extending horizontally and in communication with the interior of the valve casing, a container attached to and communicating with the other end of said rocker arm, an arm on said horizontal portion of said rocker arm adapted to contact with the valve body, an extension from said rocker arm, and an adjustable weight mounted on said extension, substantially as specified.

2. The combination with a liquid supply pipe, of a valve casing attached to said supply pipe, a discharge pipe leading from said valve casing and in communication with a tank, a valve controlling the inlet from said supply pipe to said valve casing, a counterbalanced arm having a hollow horizontal portion extending into said valve casing and in communication therewith through an opening in the wall thereof, a weight on one 115 end of said counterbalanced arm, and a container on the opposite end of said counterbalanced arm adapted to swing said arm and thereby close said inlet between the supply pipe and the valve casing when a predetermined level of water has been attained in the tank, and to discharge the contents of said container through the valve casing when the level of the water in the tank falls below the predetermined level.

3. The combination with a tank, of a valve casing in communication therewith, a supply passage entering said valve casing, a valve body in said valve casing adapted to control the flow of liquid from said supply passage to said valve casing, a hollow rocker arm having a container on one end thereof and having a branch thereof extending into and in communication with the interior of the valve casing, an adjustable weight on the 120 other end of said rocker arm, connections between said rocker arm and said valve body, whereby the valve body will be moved

to close the inlet passage when a predetermined quantity of liquid enters said container from the valve casing, and to automatically release said valve body from the intake opening when the level of the water in the tank drops below a predetermined height, substantially as specified.

In witness whereof, I have signed this specification in the presence of two subscribing witnesses.

WILLIAM JAMES HAYNES.
